LETTER HOLDER FOR MAIL BOXES

Luther H. Hoover, Waukesha, Wis.

Application May 9, 1932. Serial No. 610,083

1 Claim. (Cl. 232—33)

This invention relates to letter holders for mail boxes and the main object is to provide a device which may be attached to the lid or door of a mail box and which will hold "outgoing" letters in such position when the box is opened that they will be readily seen by the mail man and may be conveniently removed by him.

Another object is to provide a device of this kind in a simple, inexpensive, durable and efficient form.

With the foregoing and other objects in view the invention resides in the novel construction and arrangement of parts as hereinafter set forth and claimed, reference being had to accompanying drawing wherein:

Figure 1 is a side view of the letter holder mounted on the door of a mail box, the door and box being shown in cross section.

Figure 2 is a section along the line 2—2 in Figure 1.

Figure 3 is an enlarged cross section through the letter holder alone.

Referring now more particularly to the drawing my invention comprises a fixed jaw 1 formed of a substantially U-shaped piece of metal including the leg forming said jaw 1, a base 2 and a shorter leg 3 parallel with and spaced from said jaw 1. The structure thus formed is secured to a base block 4 by screws 5 passed through the said base 2, the shorter leg 3 being disposed in alignment with one longitudinal edge of the block 4 as shown. Both the jaw or leg 1 and the leg 3 have medially located and longitudinally extended slots 6 cut in substantial alignment with the face of the base 3 and the flat tang 7 of a rectangular movable jaw 8 is slidably mounted through these slots. The jaw 8 is bent at right angles to the tang 7 which extends from one edge of the jaw as shown, whereby said jaw will rest in parallel alignment with the fixed jaw 1. The end of the tang 7 is bent to provide an offset stop ear or head 9 and an expansion coil spring 10 is placed over the tang and braced between the leg 3 and the edge of the block 4 and the ear 9 as shown, the said spring thus acting to normally hold the movable jaw 8 against the fixed jaw 1.

The device is adapted to be secured to the door A of the usual mail box B or in any other suitable location but preferably so that the letters will be held within the box until the door is opened and will then be presented in position for their ready removal by the postman. Screws 11 may be extended through the door A and into the base block 4 to hold the device in place. The flat tang

7 prevents the jaw 8 from turning or twisting relative to the jaw 1.

In use the head 9 of the tang 7 is pressed toward the jaw assembly causing the movable jaw 8 to move away from the fixed jaw 1 and forming a cleft into which a letter or other object as indicated in the drawing by the dotted lines C may be inserted. Pressure on the tang 7 is then released and the spring 10 holds the jaws tightly together on the letters therein. The postman may readily remove the letters by pressing on the tang as set forth or preferably by simply pulling the letters from the jaws and it will be understood that he may thus easily and quickly remove the letters even when heavily gloved and without removing his gloves. Further details of the use of the invention will be apparent without additional description and it will be understood that the device may also be used for purposes other than holding letters and the like with equal facility.

While I have herein set forth a certain preferred embodiment of my invention it is understood that I may vary from the same in minor structural details so as best to construct a practical device for the purposes intended, not departing from the spirit of the invention and within the scope of the appended claim.

I claim:

In a device of the kind described, a base block, a fixed jaw comprising a U-shaped member including a leg forming the said fixed jaw, a base, and a shorter leg spaced from the jaw, the said member being secured by its base to the base block with the shorter leg in alignment with one edge of the base block, the said jaw and shorter leg having elongated slots in alignment with the face of the base of the U-shaped member, a movable jaw, a flat tang extended at right angles from the jaw and slidably passed through the said slots in the U-shaped member, an ear bent from the end of the tang, and an expansion coil spring braced between the said ear and the base block and shorter leg of the U-shaped member.
